US0D1004556S

(12) **United States Design Patent** (10) **Patent No.:** **US D1,004,556 S**
Wang (45) **Date of Patent:** **** Nov. 14, 2023**

(54) **ELECTROSTATIC WIRE WINDER**

(71) Applicant: **INTRADIN (HUZHOU) PRECISION TECHNOLOGY CO., LTD.**, Zhejiang (CN)

(72) Inventor: **Xiaocui Wang**, Zhejiang (CN)

(73) Assignee: **INTRADIN (HUZHOU) PRECISION TECHNOLOGY CO., LTD.**, Huzhou (CN)

(**) Term: **15 Years**

(21) Appl. No.: **29/807,204**

(22) Filed: **Sep. 9, 2021**

(51) LOC (14) Cl. **13-99**

(52) U.S. Cl.

USPC **D13/199**; D8/358

(58) **Field of Classification Search**

USPC **D8/358, 359; D13/199, 153**

CPC **H02G 11/02**

See application file for complete search history.

(57) **CLAIM**

The ornamental design for an electrostatic wire winder, as shown and described.

DESCRIPTION

FIG. 1 is a perspective view of an electrostatic wire winder showing our new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top view thereof; and,

FIG. 8 is a bottom view thereof.

The broken lines shown on the drawings depict portions of the electrostatic wire winder that form no part of the claimed design.
